UNITED STATES PATENT OFFICE.

HERBERT C. WHITNEY, OF REDLANDS, CALIFORNIA.

CRUDE-OIL BURNER.

1,192,589.

Specification of Letters Patent. Patented July 25, 1916.

Application filed August 31, 1915. Serial No. 48,205.

To all whom it may concern:

Be it known that I, HERBERT C. WHITNEY, a citizen of the United States, residing at Redlands, in the county of San Bernardino and State of California, have invented new and useful Improvements in Crude-Oil Burners, of which the following is a specification.

My invention relates to an oil burner and 10 in particular to a burner using crude oil as fuel.

It is an object of this invention to devise a crude oil burner, which is simple in construction and positive in operation. The 15 fuel is sprayed into the combustion zone by means of a steam jet, and means are provided for thoroughly atomizing the fuel, whereby a colorless, smokeless flame and perfect combustion are produced.

20 With these and other objects in view, which will appear as the description proceeds, my invention consists in the construction and arrangement of parts hereinafter described and claimed.

25 In the accompanying drawings which form a part of this specification, I have illustrated a convenient and practical embodiment of my invention, and in which,

Figure 1, is a side elevation of the burner 30 showing its arrangement in a furnace. Fig. 2, is a front elevation thereof. Fig. 3, is a longitudinal cross section of the burner nozzle. Fig. 4, is an enlarged detail view of the front of the burner nozzle, and, Fig. 5, is 35 an enlarged detail view taken on line 5-5, Fig. 3.

My improved burner consists of a horizontal oil tube 10 which is closed at its forward end and provided with a cylindrical 40 nozzle 11 of smaller diameter than the oil tube 10. A horizontal oil duct 12 leads from the interior of the oil tube to the forward end of the nozzle 11, said oil duct being located in the lower part of said nozzle. A 45 larger outer tube 13 surrounds the inner oil tube 10 forming an annular chamber 16. A cap 14 with a central cylindrical bore of a size to fit the nozzle 11 closes the outer end of the tube 13, the cap being externally 50 threaded to engage the threaded outer end of the tube 13. A gland 15 closes the annular chamber 16 at the inner end, and an L shaped coupling 17 establishes communication between the inner tube 10 and an oil 55 supply pipe 18. A manually controlled

needle valve 19 arranged on said coupling controls the oil feed into the inner tube 10.

As shown in Fig. 1, the oil burner projects into the combustion space of a furnace 24 under a boiler 25. Spaced at a suitable 60 distance from the end of the nozzle is a curved deflector plate 26 which serves to deflect and spread the flame issuing from the burner nozzle. A water pipe 27 connected to any suitable supply of water projects into 65 the combustion chamber on the under side of the burner to a point adjacent to the deflector plate then turns in a horizontal direction at right angles therefrom to the other vertical side of the deflector plate extending upwardly therefrom; then horizontally again across said deflector plate; then horizontally above and to the rear of a 70 burner and enters the outer tube 13 at a steam inlet 28. A valve 29 located in said water pipe at a slight distance above said inlet 28, controls the steam from said pipe to the annular chamber 16. An inclined bore 32 of approximately the same diameter 75 as duct 12 leads from the annular chamber 80 through the upper part of nozzle 11 intersecting said duct 12 at its outer end. A small channel 33, crescent shaped in cross section, is provided between the lower face 85 of nozzle 11 and the lower interior face of cap 14. This channel 29 communicates with a vertical channel 30 formed between the cap 14 and the tube 10 with the annular steam chamber 16. As clearly shown in 90 Fig. 3, cap 14 is slightly longer than nozzle 11 thereby forming a small cylindrical recess 31 at the outer end of said cap.

The operation of my improved oil burner is as follows: Crude oil is supplied through the pipe 18 into the horizontal tube 10. In 95 order to start the burner, it is necessary to force the oil through duct 12 which may be effected in any suitable manner. The oil issuing from the nozzle is ignited by any suitable means. Steam will be generated in 100 the pipe 27 and supply the annular steam chamber 16 through the steam inlet port 28. The steam jacket serves to heat the crude oil within the tube 10 to render the same more fluid, and may partly vaporize the same. 105 The steam issuing through the duct 32 will create a suction on the injector principle and will cause oil to issue from the feed duct 12. The steam duct 32 is downwardly inclined, and the steam and oil jet issuing 110

therefrom will intersect the horizontal steam jet issuing from the steam duct 33. The intersection of these two steam jets effects an intimate mixing and spreading of the fuel 5 in the combustion chamber. The water supply with which pipe 27 is connected is under a sufficient head, so as to overcome the pressure of the steam generated in said pipe. It should be noted that the steam and water 10 pipe 27 is not located in the direct path of the flame but is disposed adjacent the outer edges of the deflector plate.

It will be understood that the steam may be supplied to the steam jacket 16 directly 15 from boiler 25 or any other suitable source of steam.

While I have shown the preferred form 20 construction of the burner by those skilled

in the art without departing from the spirit of my invention as covered by the appended claim.

I claim:

An oil burner comprising a horizontal oil 25 feed tube, a valve controlled oil supply pipe communicating therewith, a steam jacket surrounding said feed tube, valve controlled means supplying steam to said jacket, a burner nozzle provided with a reduced horizontal oil duct communicating with said feed tube, a steam duct extending from the outlet of said oil duct at an angle to said steam jacket and a second steam duct located below the outlet of said oil duct for 30 spreading and atomizing the fuel, said steam ducts being inclined to each other.

In testimony whereof I have signed my name to this specification.

HERBERT C. WHITNEY.
